Primary Examiner—Melanie H Tung

(74) Attorney, Agent, or Firm—Banner & Witcoff, Ltd.

(57) CLAIM

The ornamental design for an icon for a portion of a display screen, as shown and described.

DESCRIPTION

The FIGURE is a front view of an icon for a portion of a display screen showing our new design.

The broken line showing of the portion of a display screen is for illustrative purposes only and forms no part of the claimed design.
